C. A. WOOLSEY

MILK CRATE

Original Filed Oct. 21, 1922

Patented Aug. 19, 1924.

1,505,682

UNITED STATES PATENT OFFICE.

CHARLES A. WOOLSEY, OF MINNEAPOLIS, MINNESOTA.

MILK CRATE.

Application filed October 21, 1922, Serial No. 596,081. Renewed December 26, 1923.

To all whom it may concern:

Be it known that I, CHARLES A. WOOLSEY, a citizen of the United States, resident of Minneapolis, county of Hennepin, State of Minnesota, have invented certain new and useful Improvements in Milk Crates, of which the following is a specification.

The object of my invention is to provide means on the lower slats of the walls of the crate which will protect them from breakage or damage and will form a comparatively smooth surface for convenience in sliding the crate on the floor of the car or platform.

15 A further object is to provide a runner-like attachment for the lower edge of the bottom crate slats which will not only strengthen the crate at this point but will aid in binding the walls securely together at the corners, thereby providing a receptacle that is extremely strong and durable and adapted to withstand rough usage to which articles of this kind are frequently subjected.

20 25. The invention consists generally in various constructions and combinations all as hereinafter described and particularly pointed out in the claims.

In the accompanying drawings forming part of this specification,

Figure 1 is a side view of a milk crate embodying my invention;

Figure 2 is a view of the corner of the crate partially in section;

30 35. Figure 3 is a sectional view on the line 3—3 of Figure 2;

Figure 4 is a sectional view on the line 4—4 of Figure 3;

40 45. Figure 5 is perspective view of one of the lower slats or bars removed from the crate.

In the drawing, 2 represents the lower side slat or bar of the crate and 3, the corresponding end slats.

50 55. Above the slats 2 and 3, similar slats 4 and 5 are provided; the slat at the top being separated from the adjacent slat as shown in Figure 1 to provide a hand-hold and also to allow freedom of circulation of air through the crates when they are stacked or piled one upon the other. Angle plates 6 and 7 are provided at the corners on the inside and outside of the crate, and corner plates 8 are provided at the lower ends of the angle plates and secured through the walls by a suitable means such as rivets

9 and are adapted to form feet to protect the corners of the crate and form a substantial support therefor when they are piled upon a car floor or platform or upon one another.

For the purpose of protecting the lower edges of the slats of the crate, I provide metallic straps or bands 10 fitting the lower edges and corresponding substantially to the width of the same and secured thereto by rivets 11. As shown at 12 in Figure 2, the under surface of the slat is preferably recessed and the edge of the opening in the strap through which the rivet extends is 70 pressed into the recess and securely clamped therein by the head of the rivet. The rivets extend entirely through the slats and their upper ends are headed upon suitable washers so that the bands are firmly secured to the lower exposed edges of the slats and 75 form runner-like surfaces on which the crate may be moved.

At the ends, the slats have recesses 13 therein and the bands are offset at 14 to fit these recesses and lacing wires 15 are provided having hooked ends 16 which pass through the ends of the bands 10 and through the inwardly turned ears 17 of the angle corner plates and also through ears 18 which are formed on said plates and inwardly turned between the longitudinal abutting edges of the slats, forming the wall of the crate. The end walls have their lower slats provided with bands 10^a corresponding to the one described with reference to the side walls, and secured in the same manner to the lower slats of the end walls. In this way, the protecting bands 90

are rigidly secured to the lower slats of the crate and the end slats abut those on the side, and the joint between them is concealed and protected by the angle corner plates and the plates 8. In this way, there is a continuous metallic surface covering the entire exposed lower edges of the crate not only at the corners but between the corners, and the crates may be moved or pushed from place to place on the floor of a car or platform and may be piled one upon the other and handled as roughly as articles of this kind usually are without danger of damage or breakage.

I claim as my invention:

1. A container having side and end slats at the bottom, and protecting corner plates, said end slats abutting the side slats at the

corners and both slats at the corners having recessed lower edges, metallic bands secured to the lower edges of said lower slats and offset to fit said recesses, said corner plates having ears folded inwardly within said recesses, and a lacing means passing through said ears and said bands, and said slats and securing them together.

2. A milk crate having bottom, side, and 10 end slats metallic bands fitting the lower edges of said slats and secured thereto, the ends of said slats being in abutting relation at the corners of the crate, angle plates covering and concealing the joint between 15 the abutting ends of said slats, and a lacing means passing through said slats and said corner plates, and said bands, and securing them together.

3. A crate having side and end slats at 20 the bottom, metallic bands fitting the lower edges of said slats and secured thereto, the ends of said slats being recessed, and said bands being offset to fit said recesses, and corner plates secured to said slats and concealing the joint between them, and fitting 25 said recesses, the under surfaces of said corner plates being flush substantially with the corresponding surfaces of said bands.

4. A container having side and end walls, 30 metallic bands fitting the lower edges of said walls and secured thereto and forming runners for moving the container from place to place, the abutting lower edges of said walls being recessed and said bands 35 having offsets therein to enter said recesses, means for covering said recesses and the

joints between the bands of said side and end walls, and lacing means passing through the ends of said bands and said walls and binding them together.

5. A container having side and end walls, 40 metallic bands fitting the lower edges of said walls and secured thereto and forming runners for moving the container from place to place, the abutting lower edges of said walls being recessed and said bands having offsets therein to enter said recesses, means 45 for covering said recesses and the joints between the bands of said side and end walls.

6. A container having side and end walls, 50 metallic bands fitting the lower edges of said walls and secured thereto and forming runners for moving the container from place to place, the abutting lower edges of said walls being recessed and said bands having offsets to enter said recesses, and corner irons for covering said recesses and the joints between the bands of said side and end walls.

7. A container having side and end walls, 55 metallic bands fitting the lower edges of said walls and secured thereto and forming runners for moving the container from place to place, corner irons for covering the 60 joints between the bands of said side and end walls and having their under surfaces flush substantially with the corresponding surfaces of said bands.

In witness whereof, I have hereunto set 70 my hand this 18th day of October, 1922.

CHARLES A. WOOLSEY.
